UNITED STATES PATENT OFFICE.

WILLIAM L. BLACK, OF FORT MCKAVETT, TEXAS.

PECAN-CRACKER.

1,227,570.

Specification of Letters Patent. Patented May 29, 1917.

Application filed February 13, 1917. Serial No. 148,380.

To all whom it may concern:

Be it known that I, WILLIAM L. BLACK, a citizen of the United States, residing at Fort McKavett, in the county of Menard 5 and State of Texas, have invented a new and useful Pecan-Cracker, of which the following is a specification.

The present invention appertains to nut crackers, and aims to provide a novel and improved appliance adapted especially for cracking pecans in a thoroughly efficient manner, and enabling the kernels or meats to be removed without breaking or injuring the halves thereof.

It is a difficult matter to break the shells of pecans without bruising or breaking the kernels, and it is the object of this invention to provide novel crushing heads for receiving and acting upon the pecans for effectually cutting and crushing the shells thereof, without injuring the kernels to any objectionable extent, this being accomplished by providing each crushing head with means for cutting and loosening the end or tip of the pecan, and a hole for receiving said tip or end, in connection with means to bear against the body of the shell next to the tip or end which is cut off to bulge said body and break it, thereby enabling the entire shell to be removed from the kernel in the desired manner.

The invention embodies a crusher head of novel construction for the intended purposes, and means for ejecting the ends or 35 tips of the pecans from the hole.

With the foregoing and other objects in view which will appear as the description proceeds, the invention resides in the combination and arrangement of parts and in 40 the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:

Figure 1 is a plan view of the device. 50 Fig. 2 is a side elevation thereof.

Fig. 3 is a cross section on the line 3—3 of Fig. 2.

Fig. 4 is an enlarged section on the line 4—4 of Fig. 4 of one crushing head showing a pecan applied thereto.

Fig. 5 is a view similar to Fig. 3, illustrating a modification.

Fig. 6 is an end view of still another form of crushing head.

Fig. 7 is a section on the line 6—6 of Fig. 5.

In carrying out the invention, there is provided a suitable frame 1 which can be set upon a table or other supporting member, the frame having the end pieces 2 and 65 the brackets 3 to extend under the support. A clamping screw 4 is carried by the brackets 3 to clamp the frame upon the support. A double or right and left hand screw 5 is journaled to the ends of 70 the frame, and a crank 6 or other suitable means is attached to one end of the screw for rotating it. A pair of nuts 7 are mounted upon the screw to be moved toward and away from one another when the screw 75 is rotated in opposite directions, and said nuts have the members 8 carrying the crushing heads, each member 8 carrying three heads opposing the heads of the other member, and the pairs of heads are of different 80 sizes whereby various sizes of pecans can be readily and properly cracked, which is not possible with a single pair of crushing heads, due to the variation in the sizes of pecans. By providing the sets of crushing 85 heads, various sizes of pecans can be applied to the respective crushing heads, to accomplish the desired result.

Considering the construction of one crusher head in detail, the same embodies a 90 sleeve or bushing 10 fitted within an opening 9 in the respective member 8, which opening can be tapered, if desired, and the sleeve 10 is provided at its forward end with an outstanding annular flange or collar 11 95 seating against the member 8, thereby preventing the sleeve from being forced through the opening 9 when the nut is crushed. The bore or opening of the sleeve 10 is flared at its forward end or mouth to 100 provide a continuous annular beveled surface 12 to fit snugly against the body portion of the shell of the pecan, as will hereinafter more fully appear. As shown in Fig. 3, a tubular member or bushing 13 is 105 threaded into the sleeve 10 from the rear end thereof, and its forward end is beveled reversely to the flaring or beveling of the end of the sleeve 10, to provide a forwardly and inwardly projecting annular cutting 110

edge 14 terminating short of the forward end of the sleeve 10 but located within and spaced from the beveled surface 12. The bushing 13 can be readily removed from the sleeve 10 for purpose of replacement or repair, and the sleeve can also be removed from the member 8 for the same purposes. Stems or pins 15 are carried by the ends of the sleeve and project toward one another, the free ends of said pins being enlarged, as at 16, and projecting within the holes of the crushing heads. The pecan is placed between the proper crushing heads when they are separated, and when the pecan is placed between the crushing heads, the same are forced toward one another by rotating the crank 6 in the proper direction. The annular cutting edge 14 of each crusher head will then be brought into engagement with the shell of the nut around the respective end or tip thereof, as seen in Fig. 3, the beveled surface 12 being of sufficient diameter to be spaced from the body of the nut when the cutting edge 14 contacts with and penetrates the shell. The movement of the crushing heads toward one another will cause the cutting edge 14 of each head to penetrate the shell and thereby sever said end or tip of the nut, which can move on into the central hole of the head, the edge of the body of the shell lodging in the annular groove or grooved seat between the cutting edge 14 and surface 12, and the body of the shell resting against said surface, so that when the crushing heads move toward one another farther, the body of the shell will be bulged outwardly between the heads, thereby cracking it, without crushing or breaking the kernel. Then when the crushing heads are separated, the nut will drop from between them or can be removed by hand, and the ends or tips of the shells may remain in the holes of the crushing heads, while the body of the shell which is cracked, will readily fall off, thereby leaving the kernel in uninjured condition. It will be noted that when the crushing heads are separated or retracted, they will be moved over the pins 15 which will eject the ends or tips of nuts from the holes of the crushing heads, thereby preventing clogging. The pins 15 in projecting into the holes of the crushing heads, will also prevent the nuts 7 and their members 8 from turning out of position. Said pins therefore serve to guide the crushing heads toward and away from one another in alinement. Particular attention is directed to the fact that the crushing head is provided with a hole for receiving the end or tip of

the pecan, with means within the mouth of said hole for cutting off the tip or end of the shell, and with means adjacent to and immediately outside of the aforesaid means to bear against the body of the shell and force it toward the opposite crushing head, whereby to bulge and break the shell away from the kernel.

In the variation illustrated in Fig. 4, the sleeve 10' is fitted within the opening 9 of the member 8, and has the flange or collar 11' bearing against said member, the forward end of the sleeve being flared to provide the annular bevel 12'. The bushing 13' is fitted in the sleeve 10' from its forward end, and seats against a shoulder 14^a with which the sleeve is provided within its bore, thereby preventing the bushing 13' from being forced rearwardly within the sleeve 10' beyond the desired point. The forward end of the bushing 13' has the cutting edge 14' corresponding to the cutting edge 14 above described.

In the modification illustrated in Figs. 5 and 6, the sleeve 10'' which fits in the opening 9 has the flange or collar 11'' bearing against said member, and the forward end of the bore of the sleeve is flared to provide the annular beveled surface 12''. The sleeve is provided with an annular series of inwardly projecting cutting teeth 14'' adjacent to the surface 12'', and providing an interrupted annular cutting edge instead of a continuous annular cutting edge as in the forms of crushing heads above described. The teeth 14'' serve to cut or break off the end or tip of the shell, the body of which will then bear against the surface 12'' to be bulged or expanded and then broken. This modification eliminates the bushing, since the teeth 14'' can be integral with the sleeve.

Having thus described the invention, what is claimed as new is:—

A nut cracker embodying a crushing head provided with a hole to receive the end of a nut, a flared beveled portion at and surrounding one end of the hole, and a cutting edge adjacent to and projecting within said beveled portion and beveled reversely thereto to provide a grooved seat for the edge of a shell when cut.

In testimony that I claim the foregoing as my own, I have hereto affixed my signature in the presence of two witnesses.

WILLIAM L. BLACK.
